FREDRIK ZWIEBEL, OF PROSPECT PARK, NEW JERSEY

FEELER MOTION FOR LOOMS

Application filed June 21, 1929. Serial No. 372,573.

The object of this invention is to provide a feeler mechanism for looms of the so-called "side-swipe" class which will not perform its side-swipe movement prematurely, as due to 5 the pointed or conical end instead of the cylindrical part of the wound package being presented thereto, and which, instead of requiring a special or extra-formed mass or "bunch" of windings to be provided as a 10 serve which will remain definitely attached to the core of the package, is adapted to perform said movement when a predetermined part of the regular windings, definitely remaining attached to said core, is left.

15 In the drawing,

Fig. 1 is a plan of so much of a loom, embodying the invention, as is necessary for illustration of the latter;

20 Figs. 2 and 3 are sections on line 2—2, Fig. 1, showing the involved parts in different positions;

Figs. 4 and 5 are sections on lines 4—4 and 5—5, Fig. 1; and

25 Fig. 6 illustrates the condition of the wound package just prior to the side-swipe movement.

1 designates the fixed structure and 2 the lay of the loom, and 3 is the shuttle which reciprocates as usual on the lay and contains 30 the wound filling package including a quill or other core 4 and the windings 5, the mass of which initially will as usual be conical or pointed in form as shown by the dotted outline in Fig. 6.

35 The said fixed structure here includes the breast-beam 1^a and a plate-like bracket 6 projecting therefrom in a horizontal plane, this bracket having a cover-plate 7 secured thereto by a screw 8. The bracket has a top recess 9 and each side of the recess a rabbet 10 extending toward the lay, and arranged to move in this recess is a slide 12 whose side edges are rabbeted at 13 to fit the rabbets 10 of the bracket and which is normally urged 40 toward the lay, that is, so as to abut a stop 14 of the bracket, by a spring 15 interposed between the slide and a stop 16. On this slide is pivoted to move in a horizontal plane a lever 17, its pivot being at 18; this lever is made 45 adjustable in its plane of movement by a

thumb screw 19 which by means of collars 20 thereon it swiveled in the wall 14 and is tapped into a stud 21 pivoted in the lever.

On the carrier which is thus formed by the slide 12 and lever 17 is fulcrumed a pair of 55 feeler-levers 22—23, these being also arranged in a horizontal plane, or more specifically, a plane cutting the filling package. One of these feeler-levers is fulcrumed on the lever 17, as at 24; the other (22) is fulcrumed 60 on the pivot 18 of said lever. The two feeler-levers project toward the lay, one (23) nearer thereto than the other and also being in the present instance the one which relatively adjoins the end of the package. The two feeler-levers are connected by a link 25 so that they move together on their fulcra in unison. Their ends adjoining the filling package are roughened so as to grip the windings, to which they are admitted in the usual way 70 by a slot 3^a in the shuttle.

What means is actuated by the feeler mechanism so far described, whether it be to cause stopping of the loom or to replenish the filling in some way, is not material. One form 75 of such actuated means is shown in the drawing, being substantially like that set forth in the Jennings Patent No. 1,692,992. That is to say, a controller 26 is pivoted on a stud 27 and is connected by a link 28 with a lock-lever 29 pivoted to the breast beam at 30 and weighted at 29^a (Fig. 1). This lock-lever normally abuts the projection 31 of a shield 32 weighted at 33 so as to assume the position shown in Fig. 3 when it is released by 85 the lock-lever. This shield is fulcrumed on the rolling-rod 34 which when rotated causes stopping of the loom and which carries a bunter 35. When the shield is in the position of Fig. 2 it will fend a spring-controlled dagger 36 on the lay clear of the bunter 35, but if the shield is allowed to assume the position of Fig. 3 said dagger will engage the bunter at its notch 35' and turn it and consequently the rolling-rod (Fig. 3) to stop 90 the loom. At 37 is part of the means for resetting the shield in engagement with the lock-lever.

95 The wound package may be formed by what is known as the traverse-wound method (in 100

which the layers of windings are successively advanced toward one end of the core) or otherwise so that in the unwinding more and more of the length of the core will be exposed: see Fig. 6, showing a nearly exhausted package.

In certain general respects the operation of the structure comprising the carrier and feeler-levers simulates that of the corresponding structure in the mentioned Jennings patent and others of that class; that is, so long as the feeler-levers (either of them) obtain a skid-preventing hold on the package said structure simply is idly repressed by the package when the lay moves back, but if the package allows skidding thereon, so that the feeler-levers swing on their fulcra, actuation of the aforesaid actuated mechanism will obviously result through the consequent displacement by feeler-lever 22 of part 26. It will be understood that the normal position of the feeler-levers is substantially that shown in Fig. 1, where 22 abuts 26 and the two feeler-levers form with the axis of the package acute angles pointing in the same direction—specifically, acute angles whose salient sides relatively adjoin the pointed or conical end of the package.

There is a tendency for such skidding or slippage to occur when the conical end of the package, as occasionally happens, registers with the more advanced end of feeler-lever 23; but this tendency is prevented from becoming an actuality, so that premature actuation of said actuated mechanism is avoided, by the feeler-lever 22 at that time obtaining a non-skid contact with the cylindrical part of the package.

Absence of windings being in the operation of mechanisms of this class the cause of the skidding or slippage which is in turn responsible for actuation of the actuated mechanism, it of course follows that effectual if not all connection of the filling with the shuttle is disestablished. For this reason it is usual in the use of this class of feeler mechanisms to wind the package with a special or extra-formed mass or "bunch" of windings. By my invention this is not necessary. Thus: Whatever tendency the feeler-lever 23 has to skid or slip on the hard surface of the quill or core 4 whenever it touches the same as the unwinding gradually exposes more and more of the length thereof is opposed by the feeler-lever 22 which remains in contact with the windings up to that stage where a predetermined mass is left (as the mass 5^a, shown remaining on the quill in Fig. 6): on reduction of that mass, since it no longer affords a grip to the feeler-lever 22, the slippage occurs. The mass 5^a, it will be seen, is simply the initial part of the regular windings, and of course when actuation of the actuated mechanism occurs it preserves the filling in connection with the

shuttle just as does the usual "bunch". The quantity or thickness of this mass may be varied according to requirements, to wit, by manipulating screw 19 so as to alter the extent to which feeler-lever 23 projects toward the quill farther than feeler-lever 22.

It is not indispensable that one lever project toward the package further than the other, though usually that will be the case: the advantage of the potential two-point contact is that if at one point there is for any reason tendency toward premature slippage at the other point there may be resistance to such slippage.

It is not new to provide for the feeler mechanism having a potential two-point contact with the package; but where this has been heretofore proposed there was in effect but a single lever having two arms or equivalents affording the double contact and not two levers, pivotally interlinked, each affording a contact and each having a fulcrum independent of that of the other lever, as in accordance with this invention.

Having thus fully described my invention what I claim is:

1. In a loom, the combination, with the fixed structure and also the reciprocating lay thereof and with a shuttle on the lay having the axis of its contained filling package extending lengthwise of the lay, of a feeler mechanism comprising a carrier on said structure yieldable in one and normally urged in the other direction in which the lay reciprocates, a pair of feeler levers having independent fulcra in the carrier and each adapted to contact with the package and offset lengthwise of and projecting toward said axis and forming therewith acute angles pointing in approximately the same direction and each movable on its fulcrum in a plane cutting the package lengthwise thereof, and means to transmit pivotal movement from each lever to the other.

2. In a loom, the combination, with the fixed structure and also the reciprocating lay thereof and with a shuttle on the lay having the axis of its contained filling package extending lengthwise of the lay, of a feeler mechanism comprising a carrier on said structure yieldable in one and normally urged in the other direction in which the lay reciprocates, a pair of feeler levers having independent fulcra in the carrier and each adapted to contact with the package and offset lengthwise of and projecting toward said axis and forming therewith acute angles pointing in approximately the same direction and each movable on its fulcrum in a plane cutting the package lengthwise thereof, and means pivotally linking said levers together for movement on their fulcra in unison.

3. In a loom, the combination, with the fixed structure and also the reciprocating lay thereof and with a shuttle on the lay hav-

ing the axis of its contained filling package extending lengthwise of the lay of a feeler mechanism comprising a carrier on said structure yieldable in one and normally urged in the other direction in which the lay reciprocates, a pair of feeler levers having independent fulcra in the carrier and each adapted to contact with the package and offset lengthwise of and projecting toward said axis one nearer thereto than the other and forming therewith acute angles pointing in approximately the same direction and each movable on its fulcrum in a plane cutting the package lengthwise thereof, and means to transmit pivotal movement from each lever to the other.

4. In a loom, the combination, with the fixed structure and also the reciprocating lay thereof and with a shuttle on the lay having the axis of its contained filling package extending lengthwise of the lay, of a feeler mechanism comprising a slide on said structure yieldable in one and normally urged in the other direction in which the lay reciprocates, a feeler lever fulcrumed on the slide, a supporting member adjustable on the slide, another feeler lever fulcrumed on said member, said levers being each adapted to contact with the package and offset lengthwise of and projecting toward said axis and forming therewith acute angles pointing in approximately the same direction and each movable on its fulcrum in a plane cutting the package lengthwise thereof, and means to transmit pivotal movement from each lever to the other.

In testimony whereof I affix my signature.
FREDRIK ZWIEBEL.
